UNITED STATES PATENT OFFICE

HERBERT BUCHSBAUM, OF CHICAGO, ILLINOIS

MOUNTING WALL PLATES

Application filed January 4, 1929. Serial No. 330,329.

My invention relates to the mounting of wall plates or covers for electric outlets of wall switch boxes and the like and has for its principal object the provision of a novel mounting whereby a decorative cover plate for such outlets or boxes may be readily attached or detached without danger of marring or in any way detracting from the appearance of the decorated plate.

More particularly it is the object of this invention to provide a decorative cover plate for switch boxes and the like that may be attached to the switch boxes in such a manner as to present no screws or other unsightly attaching means.

Other objects and advantages of the invention will appear as the description proceeds in connection with the accompanying drawings. However, I wish it to be distinctly understood that I do not intend to limit myself to the exact details shown and described, but that I intend to avail myself of all such modifications as would occur to one skilled in this art and as fall within the scope of the claims.

In the drawings:

Fig. 1 is a front view showing the decorative wall plate mounted in position on a switch box;

Fig. 2 is a view of the back side of the decorative plate and the attaching member or plate as they appear when detached from the wall box; and

Fig. 3 is a vertical section on the line 3—3 of Fig. 2 illustrating the cover plate as mounted upon a switch box.

Referring now in detail to the drawings, the numeral 5 indicates a wall having mounted therein the switch box 6 which is secured in the usual manner as by means of the screws 7 and 8 and which has projecting outwardly therefrom the switch lever 9. The cover plate construction consists of an inner member 10 and the outer decorative plate 11 which may be suitably decorated to conform to the color scheme of the room in which it is placed. The inner member 10 consists of a plate having the side edges 12 and 13 offset or turned inwardly so as to aid in spacing the device from the wall and which has at 14 an aperture

of sufficient size to admit the switch lever 9.

The plate 10 is also cut away at 15 and 16 to provide guide members at 17, 18, 19, and 20, the purpose of which will presently appear. At the remote ends of the cut away portions 15 and 16 and spaced slightly therefrom, the plate has struck out flanges 21 and 22 which flanges are adapted to bear against the switch box 6 as shown clearly in Fig. 3 to maintain the proper spacing of the main body of the plate 10 from the switch box. Suitable screws 23 and 24 serve to permanently fix the plate 10 in position. Between the apertures 15 and 16 and the struck out flanges 21 and 22 there is left the small bars of material 25 and 26 which, owing to their thinness will have a certain amount of flexibility.

The decorative plate 11 has in the center thereof an aperture 27 through which the switch lever 9 may project, and, in forming this aperture, the material of the plate 11 is bent to the interior of the plate as shown at 28 and 29, and then again bent as at 30 and 31 so that the free ends of the strips 28 and 29 rest against the plate 11, and are bent slightly toward each other for a purpose which will be hereinafter more fully explained. The outer rim of the plate 11 is offset as indicated at 32 so as to rest against the wall in which the box is located and make a firm contact therewith.

Now, when the cover plate is to be mounted in position, the member 10 is first attached by means of the screws 23 and 24 to the switch box, and then the plate 11 is pressed toward the switch box with the strips 28 and 29 fitting between the guide members 17, 18, 19, and 20 and the ends 30 and 31 engaging with the bars 25 and 26. These bars having a slight resiliency, will give a sufficient amount to permit the ends 30 and 31 to slide therebetween and thereafter close in against these ends so as to clamp the plate 11 in position. Thus it will be seen that the decorative plate has nothing on the exterior thereof to detract from its appearance, and yet it is held firmly in position to cover the switch box, and cannot move laterally or vertically.

If it is desired to change the decorative scheme of the room, these plates may be readi-

ly removed by insertion of a tool through the switch lever aperture and pulling outwardly upon the plate 11.

This plate 11 is preferably provided on 5 the exterior thereof with a luminous indicator at 33 so as to make the switch visible in the dark as well as by day light.

One of the marked advantages of this structure lies in its simplicity and the few 10 parts necessary to produce the desired result. Thus the entire securing structure involves only the two plates and the screws for securing the inner plate. This makes it possible to produce the devices at a low cost and 15 also avoids difficulties in assembling them as there is nothing to get lost or out of order in shipping.

From the above description, it is thought 20 that the construction and advantages of this device will be clear to those skilled in this art; and, having thus described my invention, what I claim as new and desire to secure by Letters Patent is:

1. A cover mounting for a wall switch box 25 and the like comprising a base plate having means for permanently securing the same over the said box, and a decorative plate having an outer edge adapted to rest upon the wall, said decorative plate covering said base 30 plate, and cooperating means on said plates covered by said decorative plate for detachably holding said decorative plate in position, said last named means including a pair of members on the decorative plates extending 35 thru the base plate, said members being struck up from the material of said decorative plate to provide a switch lever aperture therein.

2. A cover mounting for wall switch boxes 40 and the like comprising a member having means for permanently fixing the same on a switch box, said member having spacing means for spacing it from said box, and having an aperture therein through which the 45 switch operating lever projects, a decorative plate having a switch lever aperture therein fitting over said member and having means projecting through the aperture in said member and frictionally engaging certain edges 50 of said member at said aperture to detachably hold said plate in position.

3. A cover mounting for wall switch boxes and the like comprising a member having 55 means for permanently fixing the same on a switch box, said member having spacing means for spacing it from said box, and having an aperture therein through which the switch operating lever projects, a decorative plate having a switch lever aperture therein 60 fitting over said member and having means projecting through the aperture in said member and frictionally engaging certain edges of said member at said aperture to detachably hold said plate in position, said last named means comprising strips struck up

from said plate to form the switch lever aperture, and bent back against said plate.

In witness whereof, I hereunto subscribe my name this 27th day of Dec. A. D. 1928.
